CLAIM

The ornamental design for a vacuum insulated bowl, as shown and described.

DESCRIPTION

FIG. 1 is a top perspective view of a new, original and ornamental design for a vacuum insulated bowl according to one embodiment of the present disclosure;

FIG. 2 is a right side elevation view of FIG. 1;

FIG. 3 is a left side elevation view of FIG. 1;

FIG. 4 is a front elevation view of FIG. 1;

FIG. 5 is a rear elevation view of FIG. 1;

FIG. 6 is a top plan view of FIG. 1;

FIG. 7 is a bottom plan view of FIG. 1;

FIG. 8 is a bottom perspective view of FIG. 1;

FIG. 9 is a top perspective view of a new, original and ornamental design for a vacuum insulated bowl according to another embodiment of the present disclosure;

FIG. 10 is a right side elevation view of FIG. 9;

FIG. 11 is a left side elevation view of FIG. 9;

FIG. 12 is a front elevation view of FIG. 9;

FIG. 13 is a rear elevation view of FIG. 9;

FIG. 14 is a top plan view of FIG. 9;

FIG. 15 is a bottom plan view of FIG. 9;

FIG. 16 is a bottom perspective view of FIG. 9;

FIG. 17 is a top perspective view of a new, original and ornamental design for a vacuum insulated bowl according to yet another embodiment of the present disclosure;

FIG. 18 is a right side elevation view of FIG. 17;

FIG. 19 is a left side elevation view of FIG. 17;

FIG. 20 is a front elevation view of FIG. 17;

FIG. 21 is a rear elevation view of FIG. 17;

FIG. 22 is a top plan view of FIG. 17;

FIG. 23 is a bottom plan view of FIG. 17; and,

FIG. 24 is a bottom perspective view of FIG. 17.
